SPINNING MULE FALLER WIRE CONTROL

Lee C. Cain and Orion P. Scott, Ozark, Mo.

Substituted for application Serial No. 483,196,
April 15, 1943. This application May 22, 1946,
Serial No. 671,588

1 Claim. (Cl. 267—1)

1

This invention relates to a faller wire control for spinning mules and is a substitute application for application Serial No. 483,196, filed April 15, 1943, now abandoned, for a Spinning mule faller wire control.

It is particularly aimed to provide an instrumentality which will control the speed of the tension wire to prevent excess strain on the yarn, and more specifically a structure which will avoid the inconvenience and trouble incidental to the breaking down of ends when the faller descends to guide the yarn for winding.

I particularly aim to provide a structure which is exceedingly simple, as a single accurate adjustment eliminates twists at roving rolls due to excess strain on yarn, one which may be fastened at the front of the mule carriage or the equivalent, one which avoids the use of rods or levers beneath the carriage, and a structure which requires merely seconds for adjustment.

The more specific objects and advantages will become apparent from a consideration of the description following taken in connection with accompanying drawings illustrating an operative embodiment.

In said drawings:

Figure 1 is a fragmentary view in front elevation of a spinning mule carriage equipped with my improvement;

Figure 2 is a transverse sectional view, fragmentary, through a spinning mule carriage showing my improvement in place;

Figure 3 is a view similar to Figure 2 showing the action in the event of breaking down of thread when the faller descends to guide the yarn for winding; and

Figure 4 is an enlarged vertical sectional view, being substantially centrally through my improvement and the adjacent part of the mule carriage.

Referring specifically to the drawings wherein like reference characters designate like or similar parts, 10 represents a fragment of a conventional spinning mule carriage. 11 is a front frame member. The yarn spindles are shown at 12, the faller wire being at 13, with which the faller 14 is associated and which is carried by the counter faller rod or shaft 15, mounted for rocking as usual.

In carrying out my invention I provide a unit having an attaching base or bracket at 16 equipped with a vertical flange 17 adapted to be bolted or riveted at 18 to the said frame member 11. Such bracket 16 forms the bottom of cylinders 19 and 20, preferably welded thereto as shown

2

and which cylinders are in communication adjacent the top by a conduit 21 and in communication at the bottom by a pipe or conduit 22 whose ends are mounted by the bracket 16 and which pipe or conduit 22 has an adjustable valve 23 connected therein to close the same or to vary the passage of fluid from one cylinder to the other, and which fluid is for instance cylinder oil.

Screw-threaded caps 24 are removably applied to the tops of the main and auxiliary cylinders 19 and 20. A suitable piston coacts with the main cylinder 19, having a head 26 therein and a stem or rod 27 slidably mounted through the cap 24, specifically through a stuffing box 28 thereon.

15 A collar or the like 29 is mounted in fixed position on the rod 27 and a link 30 is pivoted at 31 to the collar and at 32 to a crank 33 extending rigidly from the faller shaft 15.

The cylinders 19 and 20 are usually about two-thirds full of the cylinder oil O, and a coil spring 35' surrounds the rod 27, resting on the stuffing box 28 and normally at the limit of expansion in the position shown in the drawings and bearing against an abutment collar or the like 34 detachably connected to the rod 27, so that the spring 35' will tend to maintain the piston in and urge it to the position shown in the drawings.

In the event that the faller wire 13 breaks, the faller shaft 15 will rock from the normal raised position of Figure 2 to the position of Figure 3 forcing the piston 26 down in the main cylinder 19, which forces the oil or fluid from the latter into the auxiliary cylinder 20. The action of the faller wire is controlled by the adjustment of the valve 23 since it controls the flow of oil between the main and auxiliary cylinders. Spring 35' returns the piston 26 and the rod 27 to normal position.

40 Various changes may be resorted to provided that they fall within the spirit and scope of the invention.

We claim as our invention:

In a mechanism of the class described, a bracket 45 including a support-engaging portion and an outstanding horizontal plate, a pair of vertically disposed cylinders open at their upper ends and each having its lower end rigidly secured to and closed by the plate, removable caps for the upper 50 ends of said cylinders, a conduit having ends mounted through the plate and communicating with lower ends of the cylinders, said cylinders containing a volume of fluid, a valve interposed in said conduit and controlling flow of fluid between lower ends of the cylinders, an unobstructed 55

pipe extending between and communicating with upper ends of the cylinders adjacent upper ends thereof, a piston rod slideable through the cap of one cylinder and carrying a piston at its lower end located within the said cylinder and operating between the pipe and the lower end of the cylinder, a collar about said rod, and a compression spring about the piston rod engaging the collar and the last mentioned cap and urging the piston rod and the piston upwardly to a normal 10 position.
